UNITED STATES PATENT OFFICE.

ANTOINE AIMÉ REVEL, OF LYON, FRANCE.

MEANS FOR RETAINING THE ENDS OF THE RIBS OF UMBRELLAS AND THE LIKE IN CLOSED POSITION.

1,073,631.

Specification of Letters Patent. Patented Sept. 23, 1913.

Application filed November 11, 1912. Serial No. 730,584.

To all whom it may concern:

Be it known that I, ANTOINE AIMÉ REVEL, a citizen of the French Republic, residing at 5 Rue Pizay, Lyon, France, manufacturer, 5 have invented certain new and useful Improvements in Means for Retaining the Ends of the Ribs of Umbrellas and the like in Closed Position, of which the following is a specification.

10 The present invention relates to improved means for retaining the ends of the ribs of umbrellas, sunshades and the like when they are closed.

The improved means comprise the combination of a movable non-elastic ring capable of engaging over the ends of the ribs when the umbrella is closed and of sliding along the stick, with an elastic member analogous to those used in pressure buttons, 20 said member fixed to and surrounding the stick and seated against the handle of the umbrella. The elastic member holds the non-elastic ring by spring pressure when it is applied on it.

25 The annexed drawing illustrates the invention.

Figure 1 is a sectional elevation of part of an umbrella provided with the device, which is shown in the position which it occupies 30 when the umbrella is to be opened. Fig. 2 is a similar view, the umbrella being closed and the extremities of the ribs united by the movable ring which constitutes one of the elements of the device. Figs. 3, 4 and 5 are 35 respectively an elevation, a plan, and a section on line 5—5 on a larger scale of the fixed member operating to fix the ring again and the handle of the umbrella when it is open. Fig. 6 is a section on an enlarged 40 scale of the movable ring. Fig. 7 is a section of a variation of construction of the ring.

The handle A of the umbrella is mounted in the usual manner on the end of the stick 45 B of smaller diameter. The elastic member is preferably provided with a sleeve C, by means of which it is fixed by a pin or the like to the stick. D is the ring.

The member is provided at one end with outwardly turned over edges forming a kind 50 of mushroom head C² which is divided into several parts by slits C³ so as to operate as an ordinary pressure button so that it can hold the ring D on its periphery. In this position the ends of the ribs not being re- 55 tained, the umbrella can be opened or turned upside down without the ring sliding along the stick.

When the umbrella is closed it is sufficient in order to retain the ends of the ribs 60 to assemble them and then exercise a light pressure on the ring D in order to disengage it from the elastic member so that it slides over the ends of the ribs where it remains, being held by the lateral pressure ex- 65 ercised by the ends of the ribs against it. The ring can be a simple ring or provided with a cup like border or extension to engage over the ends of the ribs as shown in Fig. 7. 70

What I claim as my invention and desire to secure by Letters Patent of the United States is:—

Means for retaining the ends of ribs of umbrellas and the like in closed position, 75 comprising a member affixed to the umbrella stick and having overturned outwardly ex- 80 tended portions separated by slits to provide a resilient head, and a movable ring ar- ranged on the stick and adapted to be held 85 against the handle when the umbrella is open by engaging said resilient head, and to be removed from engagement with said head and to be placed over the ends of the ribs of the frame when the umbrella is closed to retain said ribs in the closed position, substantially as described.

In witness whereof I have signed this specification in the presence of two wit- nesses.

ANTOINE AIMÉ REVEL.
